UNITED STATES PATENT OFFICE.

BURNHAM C. STICKNEY, OF ELIZABETH, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed July 20, 1927. Serial No. 207,170.

This invention relates to the type-actions of typewriting machines, and its main object is to produce at moderate cost a system of compact, practical, staunch, efficient and durable key-trains which will not be noisy, which will manifold acceptably, and which may be readily adapted to existing standard typewriting machines.

It is the standard practice to use long and heavy type-bars, and to give the finger-keys great leverage thereon, so as to render the key-touch easy. This leverage rapidly decreases, with consequent speeding up of the type-bar, which therefore proves efficient. However, the noise of operation has proven to be a great objection to standard typewriting machines for many offices, and this invention presents a solution of the problem.

The invention aims to eliminate as far as possible the noise of the type-percussions, while preserving lightness of key-touch, and moderate depth of key-stroke. Since the types must strike upon the front or visible side of the platen, and must clear one another, they must stand far from the printing point. The arc occupied by the type-system is usually of great angular extent, so that the types at the sides of the system usually stand at sharp angles to their type-bars, as it is a disadvantage. It has been the practice in the Underwood typewriting machine to place the types about five inches from the printing point, and to make the type-bars correspondingly long, and to reduce their weight by thinning, and to increase their stiffness by corrugating them longitudinally. The type has been made to travel said five inches by depressing a key five-eighths of an inch. Shock to the operator's finger has been avoided by connecting the key to the type-bar by means of a pin-and-slot arrangement, which gave great leverage and consequent ease to the key at the start of the stroke, and which accelerated the type-bar throughout the stroke, with the effect of cushioning the operator's finger at the end of the key-stroke, and at the same time accelerating the heavy type at the completing portion of the printing stroke.

The invention deals mainly with the means for easing the key-touch, conserving the merits while eliminating the demerits of such devices. The avoidance of jar to the operator's hand at the conclusion of the stroke is, according to standard practice, due to the type-

accelerating device, the momentum of the hand being largely absorbed by the type, the hand being gradually arrested while the type is correspondingly accelerated. According to the present invention, the touch-cushioning means performs the old office of softening the initial resistance of the key to the touch, by arranging for an initial great leverage of the key upon the type. Then the leverage rapidly decreases, avoiding excessive depth of key-stroke. The type moved rapidly the most of the distance to the platen, where a diversion from standard cushioning practice is made; that is, the standard rule is followed to the extent of decreasing the leverage of the key upon the type-action (considered as a unit) throughout substantially the entire key-stroke, but during much of the last half of the key-stroke the leverage of the key upon the type itself is substantially increased, contrary to standard practice. The speed of the type (not of the entire type-action) is accordingly much reduced. It is found that all the usual advantages of cushioning the key-touch at initial and final portions are secured, and that efficiency of type-impression is also secured, but that noise of type-percussions is almost eliminated.

A system of touch-cushioning type-actions is contrived, of sufficient dimensions to give room for the types when at rest, the types for this purpose standing at a great distance from the platen, the type-linkage being of sufficient stiffness, so that, notwithstanding its extra length and its jointed condition, it is capable of pressing the type efficiently and clearly (but not too heavily) against the work-sheet, and the key-energy is so far conserved and utilized, without harshness at any point, that each type-linkage is capable of being easily set in motion even when the key is struck sharply, and the linkage is sped up during the key-stroke sufficiently to cause a strong impression of the type upon the platen, notwithstanding that the type makes but negligible sound, due to its moving much more slowly when arrested than when jumping from normal position nearly to striking position. The type-action is neither so weak and light as to make the impression depend upon high speed of the type, nor so strong and heavy as to result in undue resistance to the key when sharply struck.

The type-travel is six inches or more. Its speed, after starting, rapidly increases to a

very high point, the type nearly completing its travel while the key has yet some distance to go. While the speed of the type-action as a unit is still accelerating, it is contrived that the type itself shall slow down until it is almost in contact with the ink-ribbon, at which point its speed is but a small fraction of the speed of a standard Underwood type at the same point. The speed of the blow 10 may be reduced to perhaps 1/36 of the blow of the standard Underwood type upon the platen. This weakness of blow is due to deceleration, and it is so weak that it is nearly noiseless. The operation is found to be so 15 quiet as to bring the machine practically within the field of quiet or noiseless typewriters.

The weakness of the type-percussion does not result in weakness of the inked impression. There is no loss of momentum from the deceleration of the type; and the momentum of the operator's hand also may be fully utilized. Due to the acceleration of linkage, and deceleration of type alone, the 20 manifolding result is also excellent, and beyond what has heretofore been considered practicable in machines of the quiet or noiseless class.

The combined acceleration and deceleration device is distinguished from the usual noiseless type-actions, inasmuch as it is not self-arresting, that is, its various parts are not arrested by one another, but solely by the percussion of the type against the platen. 30 The speed of the type-action as a unit accelerates right up to the end, and is still accelerating when the type-action strikes its blow upon the platen, notwithstanding that the movement of the type itself is being rapidly decelerated just as it approaches close to the platen.

By causing the heavy double-case type to travel about six inches, the angular extent of the type-bar arc is reduced, and the same 40 is also true of the angular positions of the types on the type-bars. The planes of movement of the type-linkages are radial, intersecting at the printing point itself (above the type-guide), and each linkage lies within its 45 working plane, the types striking perpendicularly to the platen to make firm impressions, without slurring. To secure the cushioning, the type is fixed upon a link forming 50 part of a linkage which is normally folded. 55 The unfolding causes the type to move very swiftly to a position near the platen, and the continued motion of the linkage carries the type, at relatively slow speed against the platen. The type-end of said floating link 60 is moreover given preferably an extra retardation compared with the remainder of the linkage, the rearward movement of the type at this time being perhaps about one-third of the rearward speed of the free ends 65 of the other two links. In other words, the

two links move rearwardly at accelerating speed, to cushion the operator's hand and gather momentum in the linkage, while the type-end of the linkage moves rearwardly at a decelerating speed, yet is sharply arrested, 70 and the arrest of the accelerating portion of the linkage is also sharp. Although the linkage is of such moderate weight as to comport with the requisite stiffness, still the requirement of stiffness does not demand such 75 a degree of weight as to preclude soft initial resistance of the key. A linkage of these dimensions and stiffness and ease of starting, is still efficient, due to acceleration, to insure a strong and clear impression of the 80 greatly retarded type.

Other features and advantages will hereinafter appear.

In the accompanying drawings,

Figure 1 is a sectional longitudinal elevation of an Underwood standard typewriting machine, showing the present invention applied thereto; the view taken about centrally of the machine.

Figure 2 is a diagram of the key-levers, the bell-cranks connected thereto, and the slotted arms of the drive links seen at Figure 1.

Figure 3 is a view, showing the type-actions similar to Figure 1, but showing them in full lines in printing positions and in dotted lines 95 in normal positions, and also at various intervening points.

Figure 4 is a front sectional elevation of the system of type-actions, showing parallel key-levers and radiating type-linkages and 100 sub-levers.

Figure 4^a is a plan of the common lateral type-guide.

Figure 5 is a sectional plan of the machine.

Figure 6 is a sectional front elevation, showing the segments and other supports for the rear portions of the type-actions.

Figure 7 is a sectional front elevation, showing the segment-frame for the guide-links used in the linkages.

Figure 8 is a development of the types in normal positions, showing them cleared from one another, and also showing that in each case where a linkage makes an angle with its type, the intersection of angle is practically coincident with the printing point of the type.

The type-keys 10 are mounted upon stems 11 which rise from the front ends of bars 12 extending rearwardly from each keyboard, and about parallel, said bars at their rear ends being bent upwardly to form arms 13 which depend from a transverse horizontal pivot-rod 14. These U-shaped key-levers 125 operate substantially as bell-cranks, and vibrate in substantially vertical parallel planes extending from front to rear.

Said pendent arms swing rearwardly at the key-strokes, and pull rearwardly a set 130

of pull links 15 which may be pivoted in a horizontal row at their rear ends at 16 to the rearwardly-vibrating lower portions of the pendent key-lever arms 13. Said pull links 15 run forwardly, and are pivoted at 17 to the short pendent arms 18 of a system of bell-cranks 19 which radiate from the printing point 20 and are pivoted upon a curved fixed transverse fulcrum-rod 21 and work in radial slots 23 in a transverse segment 24 forming part of the framework of the machine. These bell-cranks include relatively long rearwardly-extending arms 25 which extend rearwardly from the pivots 21, 15 and at their rear ends carry pins 26 which work in radial slots 27 cut in the short arms 28 of drive links 29 of a system of normally folded type-linkages, designated generally as 30. Said type-linkages 30 radiate from 20 the printing point 20, and include the system of normally cumbent drive links 29 and a front system of upstanding guide-links 31. The drive links 29 are fulcrumed at their rear ends upon a curved pivot-rod 32 mounted in a transverse segment 33 substantially concentric with the printing point, and having radial guide-slots 34 for the links 29, which, with their slotted arms 28, form bell-cranks. The front guide-links 31 are pivoted 25 at their lower ends upon a transverse curved rod 35 in a segment 36 (integral with 24) and having radial guide-slots 37. Each of the drive links 29 is connected to its companion guide-link 31 by a floating link 38 which carries a printing type 39. The floating type-link is in the nature of an elbow, that is, a triangle is formed by the type, and the two pivots 40 and 41 which connect the type-link to the free ends of the drive and 30 guide links respectively. The slotted arm 28 is formed upon the rear or drive link 29, and the type 39 normally rests at the rear of the linkage and at a point extremely remote from the platen, whereby clearance of 35 the types from one another is secured; a padded curved rest 42 being provided for the linkages, preferably under the type ends of the floating links 38.

As the key-lever 11, 12, 13 is depressed, its 50 arm 13 swings backward, and by means of link 15 pulls on the short arm 18 of the bell-crank, and the long arm 25 thereof is swung upwardly, thereby swinging the short arm 28 of the drive link 29 forwardly and the link 25 itself upwardly and rearwardly, thus rapidly unfolding the normally cumbent floating type-bar link 38 and lifting it in a radial direction until the floating link reaches the neighborhood or about the level of the printing point, whereupon the type-link is carried or floated rearwardly upon the tops of the rearwardly-vibrating links, until the type 55 strikes the shiftable platen 43 through a vibratory ink-ribbon 44. Upon relief of the 60 key 10 from pressure, the key-action returns

with the aid of spring 45 connected with the lever-arms 13.

The slots 27 when at rest diverge but little from the paths of pins 26, thus giving great initial leverage of the keys and bell-cranks 25 upon the type-linkages rendering the key-touch easy, and this leverage rapidly decreases until about the completion of the key-stroke, so that the movement of each type-linkage as a unit is constantly accelerating, especially when it is kept in mind that considerable of the momentum of the operator's hand is absorbed by the linkage during the latter half or portion of the key-stroke. 75

It will be seen that the heavy type 39 has 80 far to travel in the unfolding movement of the linkage, and must move at high speed accordingly, but this is accomplished without rendering the key-touch harsh, inasmuch as the key has its maximum leverage upon the 85 heavy type at the beginning, so that the type starts slowly, and then makes up for lost time by making an extra spurt of speed during the remainder of the unfolding of the type-linkage. After unfolding, the movement of the 90 type is relatively slow.

The acceleration of the linkage continues throughout the printing stroke, yet the type end of the floating link decelerates in the last 95 half of the key-stroke, since at this time the movement of the type-link, which has been rapidly turned upon its two pivots at the unfolding of the linkage, begins to resemble a parallel motion, and the type advances no faster than the free ends of the drive and 100 guide links. This contrasts with the great speed of the type which prevailed during the unfolding movement. Acceleration of the linkage as a unit is secured, with resulting softness of the key-touch, and also with 105 cushioning of the operator's hand at the completion of the stroke, yet without speeding the free and heavy type against the platen and without the consequent noise of concussion heretofore usual. In changing from the 110 unfolding to parallel movement, the speed of the heavy type greatly decelerates, while the motion of the linkage as a whole is always accelerating.

Since the type at the percussion against the 115 platen has a speed no greater than that of the free ends of said drive and guide links, its momentum is so little that the noise of percussion is much reduced, as compared with standard typewriter practice. But notwithstanding the slow motion and quiet percussion of the type upon the platen, it will be understood that the entire key-action is also suddenly arrested with the type, and the shock of percussion is therefore sufficient to make a clear 120 impression upon the paper through the usual ink-ribbon 44.

Moreover, the type-link and the links which 125 carry it are so proportioned, formed and mounted that during the final step of the com- 130

pleteing portion of the type-stroke, the type may mechanically be given extra retardation, until its speed is reduced to say one-third of the speed of the free ends of the drive and guide links, thereby still further quieting the percussion of the heavy type against the platen and consequently reducing the noise thereof, while the type-impression upon the paper is clear and efficient, due to the shock of 5 arrest of the entire type-action and of the operator's hand. The pivot 41 is finally caused to swing downwardly as well as rearwardly, while the pivot 40 is swinging in about a level path, whereby the advancing type-link 10 15 20 25 30 35 40 45 50 55 60 65 70 pin 26 and the radiating slot 27, because the desired decrease in leverage is gained while all parts, from the key to the type, remain permanently articulated each to the next, and all may be controlled by the single returning spring 45 placed at a suitable point in the action. The cumbent positions of the arms 25 give a compact arrangement of 25 and 15 just under the type-linkages, and permit the draw-links 15 to work in planes about parallel with parallel arms 13, and not at harsh angles to radiating arms 18, while the line of pivots 16 may be at about the average height of pivots 17, and the width of the system of arms 13 may about equal that of the system of arms 18.

The usual operation of a leverage-decreasing device is that the type starts slowly and easily, and that as the key descends the speed of the type increases, bringing the type up to top speed at the percussion. This produces a hammer-blow which is desirable, especially for manifolding; but it is noisy. In the new organization, the parts to be started in the operation are long and heavy, but the mass is brought into movement easily, and it is contrived not to incur the usual consequence, namely, the type is not persistently speeded up as has heretofore been done. On the contrary, the type is slowed down as it approaches close to the platen, notwithstanding that the mass of linkage is itself speeded up throughout the printing stroke and is going fastest at the moment the type contacts with the paper. Thus it is rendered practicable and useful to employ a long and heavy linkage (which would otherwise be prohibitive), and to use two type-faces on a bar, and to swing the type from a point far distant from the printing point, and to speed up the linkage throughout the printing stroke, and to utilize the momentum of the operator's hand in delivering the final impact of the type, as well as the momentum of the speeded-up linkage, but with the use of a decreasing speed of the type as it approaches close to the platen; this being found to avoid noise, while at the same time securing a very fine type-impression.

The pendent arms 13 of the key-levers may have projections 53 to operate a universal bar 54, pivoted at 55 and having a pin 56 to operate an arm 57 pendent from the rocking frame 58 which is usually provided in the Underwood typewriting machine for operating the dog-rocker 59. By this means is controlled the escapement-wheel 60, having a pinion 61 meshing with a rack 62 on the usual carriage, upon which is mounted the vertically-shiftable platen 43. From the rocker 59 extends forwardly a horizontal reciprocating frame 63, upon which is mounted the slotted actuator 64 of the Underwood bichrome-ribbon mechanism, which also in-

cludes a bell-crank 65 connected by a link 66 to a rock-frame 67, which carries vertical vibrator 68 for the bichrome ribbon 44. At its upper end, the vibrator 68 may be guided by a guideway 70 provided upon the rear of the type-guide 50. The type-guide 50 may be fixed on the upper ends of arms 71 which extend upwardly from the middle of a cross-bar 72 secured at its ends upon the side framework.

It will also be noted that the distance between the free ends of the drive and guide links may be substantially less than the distance from the free end of the drive-link to the type, giving the type end of the linkage an accelerated unfolding movement during the first portion of the key-stroke, and thereafter translating the type-link bodily rearwardly at less than the speed of the free ends of the drive and guide links. The linkages are normally folded with the types facing downwardly at the rear of the guide-link fulcrums. The free end of the drive-link is near the fulcrum or fixed pivot of the guide-link. Near the printing point the movement of the free end of the guide-link is rearwardly and downwardly relatively to the free end of the drive-link, tending to rock the type-link forwardly about the free end of the drive-link, thus decelerating the type relatively to the rearwardly swinging free ends of the drive and guide links. The leverage-changing connections to the drive-link has maximum leverage on the linkage at the beginning of the printing stroke, and minimum leverage on the linkage at the completion of the printing stroke.

It will be perceived that the linkage secures high speed of the type from normal position, and thereby makes up for loss of speed when the type is nearing the platen. The high speed of type is secured by the unfolding of the linkage, the speed of unfolding being very great. After unfolding, the type proceeds to float slowly back towards the platen upon the links.

The linkage controls the speed of the type at the moment of impression and preserves the advantage of ink-ribbons. The type-linkage avoids a heavy blow with its objectionable noise. A very slow approach of the type is secured as it is in the immediate vicinity of the platen, so as to avoid the noise and to secure the type-impression by means of the impetus of the main portions of the type-linkage as well as of the key-connections and the hand of the operator. The type reaches the paper and is then subjected to great pressure from such momentum as contradistinguished from a hammer-blow which is common in typewriters.

The type finally moves through a path which is radial to the platen-axis, or at right angles to the type-lifting movement. The type-linkage is for this purpose first opened

- or extended to its fullest possible limit, at which time the type reaches the level of the printing point, and then the linkage is so proportioned and formed and located as to 5 carry the type straight back horizontally and squarely against the platen. At this time the type-motion is further substantially decelerated, while the motion of the drive-link and guide-link is accelerated, together with 10 the short arm of the type-link, the deceleration of the type being the final step by which is reached the main object of the invention. The type is moved very rapidly from normal position to a point close to the platen, and 15 then its speed is substantially decelerated while other parts of the linkage continue at top speed; thus quietness of operation is secured without substantial reduction of speed of operation of the machine.
- 20 In cutting down the speed of the type as it is close to the platen, the speed of the type is multiplied throughout the rest of the printing stroke much more than is the case in standard typewriting machines. Sufficient 25 initial leverage can be provided for the key to give it an easy touch, although starting the type rapidly into action. The great leverage can be rapidly reduced, so as to avoid undue depth of stroke of the key, and yet the type 30 can be brought up to the vicinity of the printing point with sufficient celerity to avoid cutting down the speed of operation of the keyboard. During unfolding of the type-linkage, the speed of the type is maximum, 35 and after the linkage is unfolded the type-link is floated back on the other links at a very slow speed, compared with its unfolding speed; and this slow speed is further substantially reduced by forming, proportioning and locating the links to cause the 40 type-link to retard or turn backwardly about its pivotal connection to the drive-link, so that the type is substantially retarded and slowed down.
- 45 The type lifts from normal position to the level of the printing point, and then moves rearwardly at about right angles to the direction of its lifting movement, the path of which is radial to the axis of the platen. This 50 rearward path is the same for all the types in the system, and hence it is practicable to make a center guide which will be efficient and thereby render it practicable to use this type of linkage for a typewriting machine 55 having two types on each linkage. Moreover, by moving in this path, which is perpendicular to the platen-surface at the printing point, the types are enabled to clear the type-guide. They rise in front of the type-guide, 60 and then move backwardly thereover and squarely against the platen. This makes it practicable to use a guide below the printing point, where it will not obscure vision of the typing, and to use a pendent nib on the 65 type-linkage to enter said guide.

By providing the center type-guide and also the linkage-guide near the articulation of the guide-link with the type-link, the linkage is guided very steadily and accurately to the platen, and the momentum thereof is well utilized in forcing the type against the platen, the linkage being supported against sidewise buckling or yielding, and a good impression being effected, while the key-stroke is rendered light without incurring the necessity of making the key-stroke of undue depth.

The linkage at Figure 3 is completely straightened out, that is, the two pivots of the drive-link 29 are in line with the printing point on the platen. While in this completely unfolded condition, the type has floated back slowly to the platen, and this slow motion being further retarded by the turning back of the type-link upon the drive-link, as already explained.

As understood, the double-case types 39 are set at gradually increasing angles to their links 38 from the middle to the sides of the system, and each link has a guiding nib 49 extending vertically down from the type when it is printing, and the fixed lateral common guide (Figure 4^a) is entered by said nibs just below the printing point. A movement-accelerating train extends forwardly from arm 13 to the drive link 29, said train including a transmitting link 15 and a sub-lever 25 pivoted upon the machine-frame and having a movement-accelerating engagement with the drive link, each sub-lever including a rearwardly extending arm engaging the slot 27, and a downwardly extending short arm 18. The width of the sub-lever system is approximately equal to the width of the key-lever system and the system of drive links. The line of articulations 16 of the drive links is above the middle sub-lever articulations 17 and below the sub-levers at the sides of the system, and the links incline forwardly up and down according to the positions of the sub-levers, Figure 2.

Figure 4^a shows the notched guide for the type-nibs, the notch having widely flaring sides to give clearance to the nibs at the sides of the system. The type moves slowing at this point, so that a shallow guide-notch is sufficient. The goose-necks on the type-links at the sides of the system enable the links to clear the guide, the links standing in front of the shallow guide as the type is against the platen.

At Figure 3, the key-action is shown by full lines in printing position, and by dot-and-dash lines in normal position. The printing movement of one of the keys is shown divided into five equal parts; and the type 39 is shown at corresponding positions by dot-and-dash lines. It will be seen that the type starts slowly, due to the extraordinary leverage obtained by the use of the pin 26 and slot 27 in bell-crank 29. This lever-

age rapidly decreases; and by the time that the key has made two-fifths of its stroke, the speed of the type is much increased. From this point during the next two-fifths of the 5 key-lever stroke, the movement of the type is extremely rapid. By this time the unfolding movement of the type-linkage is completed, and the type is facing rearwardly, and is about to strike. From this station on 10 wardly to the point of percussion, the type-speed rapidly decelerates, while the linkage as a unit is continually gathering speed.

At Figure 2, the line of the articulation 16 of the links 15 to the lever-arms 13 is above 15 their points of articulation 17 to the middle bell-crank 25, but below the articulation 17 of the links to the bell-crank 25 at the sides of the system. The bell-crank arms 18 may be made of various lengths, giving the keys 20 substantially uniform depth of stroke. The line of articulation 16 may be far beneath the key-lever pivot-bar 14, so as to secure ample vibration, and avoid raising the articulation 17 to a point too close to the pivot 21 of the 25 bell-crank.

Figures 6 and 7 illustrate the preferred manner of mounting the segments 24, 33, 36 that support the type-action system. The segment 33, in which the driving links 29 are 30 pivoted, is seen from the front at Figure 6. It has projections 73, whereby it may be attached to the side members of the Underwood typewriter-framework 51 by screws 74. The base 75 of the segment 33 may have a 35 flange 76 to which may be secured a spring-anchor-bar 77. The key-lever-fulcrum-rod 14 runs through a slotted bar 78, the levers working in the slots 78^a. Said bar is attached to segment 33 by screws 79. The combined segments 24 and 36 may be organized 40 as shown in Figure 7. This structure may also include the segment 82 which has the guide-slots 46. Arms 84 are attached to the typewriter-framework 51 by screws 86.

Figure 8 illustrates the manner of constructing the type-links so that the several type-guiding nibs 49 may not interfere with the goose-neck portions 48 of adjacent type-links.

As shown in Figure 8, the gooseneck-portion 50 of each type-bar may be bent sidewise at 90 to bring the center of the lower-case type 55 into the central or working plane of the type-bar. Another bend in the neck portion at 91 (coincident with the printing point) gives the proper inclination to the type-head, to make the upper-case type register with the upper-case printing point. Figure 8 is a developed plan view, showing particularly how 60 the inclination of the type-heads from the type-bar proper varies in the usual manner from a minimum inclination on the middle type-bars to a maximum inclination on the outer type-bars. In order to make the outermost angles as small as possible, the spacing

between adjacent type-bars is decreased as much as practicable throughout the system. As the centers of the lower-case types of all the type-bars lie in the central planes of their respective type-bars, Figure 8, there is avoided all the twisting stress. There is correspondingly less offsetting in the upper-case types, thereby minimizing said twisting stress as to them. It will be noted in Figures 4, 6 and 7 that the type-bar segment occupies about 80 degrees, and is substantially less than usual in the standard Underwood typewriter. The reduction of this angle entails a corresponding reduction in the individual inclinations of the type-heads, and consequently the upper-case types for the outermost type-bars do not need to be greatly offset.

The ribbon-vibrator 68 is of novel form 85 designed to clear the type-linkages. It is a combination including some standard Underwood ribbon-vibrating elements. The upper portion of the ribbon-carrier 68 is of the same form as the Underwood and works between the type-guide 50 and the platen 43. 90 The ribbon-carrier cannot be extended directly downward for connection with the usual Underwood ribbon-vibrating arm, because in this case both the carrier and arm would interfere with the type-bar movement. Hence 95 the arm 65 is shortened, and is connected by link 66 to another arm 67^a on a long transverse ribbon-vibrating rock-shaft 93. Said shaft 93 is of such length that ribbon-vibrating arms 67 at the ends thereof are outside the 100 zone of type-bar movement. The shortened arm 65 and the arm 67^a also clear said zone. The yoke-members 94 branch from 68. The extensions 94 are formed to clear the type-bars, and are pivotally connected at their ends 105 at 95 to the ribbon-vibrating arms 67.

In order that the ribbon-carrier may follow the case-shifting of the platen, the ribbon-vibrating rock-shaft 93 is journaled in three brackets 96 fastened to the rear of the 110 front rod 97 of the usual platen-shift frame. The middle of said brackets has a fulcrum for the lever 65. The upper arm of said lever 65 is of the Underwood form, having the usual two wrists 98, selectively engaged by the 115 usual actuating member. The bichrome-shifting means is of the type illustrated in Patent 926,050, to F. A. Cook, June 22, 1909.

The sides 38^a of the type-links 38 may be joined near the gooseneck-portions 48. The 120 sides may be joined directly or may be separated by spacers 87 and the joints may be secured by welding or riveting, Figures 1, 8.

The rocker 58 carries a pair of arms 63 pivoted thereto and extending forwardly and having fixed on their forward ends a cross-bar 99, from which extends forwardly a tongue 100 guided in a bracket 101 that is secured upon the cross-bar 78 of the framework. This frame, including the arms 63 and the 125

cross-bar 99, operates the dog-rocker 59 by means of a tappet 102 on the cross-bar 99. The upright bracket 64, which vibrates the ribbon, is secured upon the same cross-bar 99.

5 Claims presented herein cover broadly type-linkages and ribbon-vibrating means disclosed in my co-pending applications Serial No. 36,594 filed June 12, 1925, Serial No. 153,231 filed December 8, 1926, and Serial 10 No. 237,368 filed December 3, 1927. The claims in said copending applications are limited to features not disclosed in the present application.

15 Variations may be resorted to within the scope of the invention, and portions of the improvements may be used without others.

Having thus described my invention, I claim:

1. In a typewriting machine, the combination with a platen upon which the printing line is visible, and a center type-guide, of a system of folded radial noise-reducing type-linkages including a type-link rapidly unfoldable upwardly and then movable rearwardly slowly to the platen and capable of substantial manifolding, each linkage including a front guide-link and a rear drive or main link, each pivoted on the framework of the machine, and a cross-link pivoted upon the free ends of said links; said cross-link resembling an elbow, at the free end of which is fixed a lower and upper case type-block rigid with said cross-link, a type-rest, the types facing downwardly, a system of key-levers extending below the type-bars, and connections between the key-levers and said drive-links, said connections including a system of sub-levers operated by the key-levers and actuating the type-bars, said system of connections including automatic means for rapidly decreasing the leverage of the keys on the type-linkages throughout at least the main portion of the printing strokes whereby each type-linkage is unfolded and brought 25 easily and quickly up in front of said type-guide to striking position, and then rearwardly into the type-guide and against the platen, each cross-link being mounted upon the other links and all the links being formed, proportioned and located to effect a further slowing down of the type by means of a relative retarding swing of the cross-link upon the drive-link in a manner to effect a relative backward swing or retardation of 30 the type-end of the elbow as it approaches close to the platen, whereby the speed of the type-end of the elbow greatly diminishes while said links continue in motion at accelerating speed, to cushion the arrest of the operator's hand and the momentum of the accelerating type-action, considered as a unit, effecting a low-speed, forced, quiet impression of the type upon the platen or the paper thereon.

- 65 2. The combination with a platen, of a

system of front-strike noise-reducing type-linkages normally folded down and each at its unfolding operation swinging the type up at relatively high speed from normal position to a point near the platen, the linkage 70 including a drive-link, a guide-link, and a type-link, which, after unfolding, is floated at relatively slow speed in printing direction upon said drive and guide links, the printing movement of the type being rearwardly at substantially a right angle to the unfolding movement, the type-link having upper and lower case types rigid thereon, and keys for driving said type-linkages, each key connected to its type-linkage by a train, 80 each train including means for substantially reducing the leverage upon the linkage during the printing stroke, the speed of said linkage as a unit being thereby accelerated throughout the printing stroke, and the drive 85 and guide links being so proportioned and located and connected by said type-link that at the concluding portion of the printing stroke the type moves substantially slower than the linked ends of the drive and guide 90 links, the accelerated linkage having sufficient momentum to produce an effective printing of the retarded type without presenting undue resistance to the finger while operating the key. 95

3. In a typewriting machine, the combination with a platen upon which the printing line is visible, of a system of folded radial type-linkages movable rearwardly to strike squarely upon the platen and capable of substantial manifolding, the type-linkages being arrested by the platen only, each linkage including a front guide-link and a rear drive or main link, each pivoted on the framework of the machine, and a cross-link pivoted upon the free ends of said links; said cross-link resembling an elbow, at the free end of which is fixed a lower and upper case type-block rigid with said cross-link, a type-rest, the types facing downwardly, a system of key-levers extending below the type-bars, and connections between the key-levers and said drive-links, said connections including a set of sub-levers radiating from said drive-links, and means connecting said sub-levers 115 to backwardly and forwardly moving portions of the key-levers, said drive-links having radially-slotted short arms or hub-portions, and said sub-levers having pins engaging said radial slots, so positioned and proportioned as to start the drive-links in operation at reduced speed and with great leverage of the key upon the type-linkage, 120 greatly decreasing the leverage for the main portion of the key-stroke, said sub-levers extending transversely of said slots and said key-levers having their pivots behind the type-linkages and at about the level of the keyboard, and having forwardly and backwardly swinging portions connected to said 125 130

sub-levers by links, the main portions of the key-levers extending under the type-bars, and provided with keys at their forward ends.

5. 4. In a typewriting machine, the combination with a platen, of a system of two-case type folded noise-reducing linkages to print on the visible side of the platen, each including a rear drive link and a front follower link, both links pivoted upon the machine-frame, and a type-carrier pivoted upon the free ends of both links and having an elbow-extension carrying the type, the latter rigidly fixed upon the free end of said elbow and resting at the rear of the system of linkages, keys in front of said linkages, and driving connections from said keys to said drive links, to unfold them upwardly and rearwardly, the types moving at relatively extreme speed 20 upwardly to the vicinity of the printing point, and the links and elbow then moving together rearwardly to carry the type at about right angles to its lifting movement and radially of the platen-axis, to impress 25 the type upon the platen, said driving connections including means for giving the key an extremely great leverage upon said drive link at the beginning of the printing stroke, to start the linkage slowly in motion, and 30 said leverage decreasing substantially throughout the remainder of the printing stroke, accelerating the speed of the drive link throughout substantially its entire stroke, said type-carrier being mounted on 35 said links in a manner to substantially decelerate the type relatively to the free ends of the drive and follower links at the approach of the type radially to the platen, the contact of the type with the platen serving to arrest 40 the hand of the operator and the linkage, whereby the arrested type is subjected to sufficient pressure to make a clear impression upon the paper on the platen.

5. In a typewriting machine, the combination with a platen and a center-type-guide, of a system of two-case type folded noise-reducing linkages to print on the visible side of the platen, each including a rear drive link and a front follower link, both links pivoted upon the machine-frame, and a type-carrier pivoted upon the free ends of both links and having an elbow-extension carrying the type, the latter rigidly fixed upon the free end of said elbow and resting at the rear of the system of linkages, keys, driving connections from said keys to said drive links, to cause each of the types to move at relatively extreme speed upwardly in front of said type-guides to a point near the platen, and the 55 links and elbow then to move together rearwardly to impress the type slowly against the platen, said driving connections including means for giving the key an extremely great leverage upon said drive link at the beginning of the printing stroke, to start the link- 60

age slowly in motion, and said leverage decreasing substantially throughout the remainder of the printing stroke, accelerating the speed of the drive link throughout substantially its entire stroke, said linkages being radial to the printing point, the types setting at gradually increasing angles to the elbows from the middle to the sides of the system, each elbow having a guiding fin extending downwardly from the type, and a fixed lateral common guide entered by said guiding fins just below the printing point, said drive and follower links co-operative with said elbow-link to float the type rearwardly at slower speed than the free ends of said drive and follower links and at about right angles to the upward movement of the type from normal position, to enable the type to clear the type-guide and to drive the type 80 squarely against the platen in a direction radial to the platen-axis. 85

6. In a typewriting machine, the combination with a platen, of a system of two-case type folded linkages to print on the visible side of the platen, each including a rear drive link and a front follower link, both links pivoted upon the machine-frame, and a type-carrier pivoted upon the free ends of both links and having an elbow-extension carrying the type, the latter rigidly fixed upon the free end of said elbow and resting at the rear of the system of linkages, keys in front of said linkages, driving connections from said keys to said drive links, to unfold them upwardly and rearwardly, the types moving at relatively extreme speed upwardly to a striking point, and the links and elbow then moving together rearwardly to slow the type and impress it upon the platen, said driving connections including means for giving the key an extremely great leverage upon said drive link at the beginning of the printing stroke, to start the linkage slowly in motion, and said leverage decreasing substantially throughout the remainder of the printing stroke, accelerating the speed of the drive link throughout substantially its entire stroke, said types soldered upon said elbows, said linkages being radial to the printing point, the types setting at gradually increasing angles to the elbows from the middle to the sides of the system, each elbow having a guiding fin extending downwardly from the type, a fixed lateral common guide entered by said guiding fins just below the printing point, and a radial guide-comb for the upper ends of said following links, supporting the linkages during the forcing of the types against the platen. 115

7. In a typewriting machine, the combination with a platen upon which the printing line is visible, of a system of folded radial type-linkages movable rearwardly to strike squarely upon the platen and capable of substantial manifolding, the type-linkages being 120

- arrested by the platen only, each linkage including a front guide-link and a rear drive or main link, each pivoted on the framework of the machine, and a cross-link pivoted upon 5 the free ends of said links; said cross-link resembling an elbow at the free end of which is fixed a lower and upper case type-block rigid with said cross-link, a type-rest, the types facing downwardly, keys in front of 10 said type-linkage system, levers for said keys, each lever including a key-stem, a bar extending rearwardly beneath the type-linkages, and an arm extending up in rear of the type-linkages from said bar and pivoted at its upper 15 end, and a connecting train extending forwardly from said arm to said drive link.
8. In a typewriting machine, the combination with a platen upon which the printing line is visible, of a system of folded radial type-linkages movable rearwardly to strike 20 squarely upon the platen and capable of substantial manifolding, the type-linkages being arrested by the platen only, each linkage including a front guide-link and a 25 rear drive or main link, each pivoted on the frame-work of the machine, and a cross-link pivoted upon the free ends of said links; said cross-link resembling an elbow at the free end of which is fixed a lower and upper 30 case type-block rigid with said cross-link, a type-rest, the types facing downwardly, keys in front of said type-linkage system, levers for said keys, each lever including a key-stem, a bar extending rearwardly beneath the type-linkages, and an arm extending up in rear of the type-linkages from said bar and pivoted at its upper 35 end, and a connecting train extending forwardly from said arm to said drive link, said connecting train including a transmitting link, and also including a sub-lever pivoted upon the machine-frame and connected 40 at one end to said drive-link and having a movement-accelerating engagement with the main guide-link 45 of the type-linkage.
9. In a typewriting machine, the combination with a platen upon which the printing line is visible, of a system of folded radial type-linkages movable rearwardly to strike 50 squarely upon the platen and capable of substantial manifolding, the type-linkages being arrested by the platen only, each linkage including a front guide-link and a rear drive or main link, each pivoted on the framework of the machine, and a cross-link pivoted upon 55 the free ends of said links; said cross-link resembling an elbow at the free end of which is fixed a lower and upper case type-block rigid with said cross-link, a type-rest, the types facing 60 downwardly, keys in front of said type-linkage system, levers for said keys, each lever including a key-stem, a bar extending rearwardly beneath the type-linkages, and an arm extending up in rear of the type-linkages from said bar and pivoted at its upper 65 end, and a connecting train extending forwardly from said arm to said drive-link, springs for returning said linkages to normal positions, ribbon-vibrating means and carriage-feeding means universally engageable by the rear arms of said key-levers.
10. In a typewriting machine, the combination with a platen upon which the printing line is visible, of a system of folded radial type-linkages movable rearwardly to strike 70 squarely upon the platen and capable of substantial manifolding, the type-linkages being arrested by the platen only, each linkage including a front guide-link and a rear drive or main link, each pivoted on the framework of the machine, and a cross-link pivoted upon 75 the free ends of said links; said cross-link resembling an elbow at the free end of which is fixed a lower and upper case type-block rigid with said cross-link, a type-rest, the types facing downwardly, keys in front of said type-linkage system, levers for said keys, each lever including a key-stem, a bar extending rearwardly beneath the type-linkages, and an arm extending up in rear of the type-linkages from said bar and pivoted at its upper 80 end, and a connecting train extending forwardly from said arm to said drive-link, said connecting train including a transmitting link, and also including a sub-lever pivoted upon the machine-frame and connected 85 at one end to said drive-link and having a movement-accelerating engagement with the main guide-link of the type-linkage, said engagement including a substantially radial slot in the main guide-link hub, and a pin on said sub-lever and engaging the outer end of said slot and moving towards the pivot of the sub-lever during the printing stroke.
11. In a typewriting machine, the combination with a platen upon which the printing line is visible, of a system of folded radial type-linkages movable rearwardly to strike 90 squarely upon the platen and capable of substantial manifolding, the type-linkages being arrested by the platen only, each linkage including a front guide-link and a rear drive or main link, each pivoted on the framework of the machine, and a cross-link pivoted upon 95 the free ends of said links; said cross-link resembling an elbow at the free end of which is fixed a lower and upper case type-block rigid with said cross-link, a type-rest, the types facing downwardly, keys in front of said type-linkage system, levers for said keys, each lever including a key-stem, a bar extending rearwardly beneath the type-linkages, and an arm extending up in rear of the type-linkages from said bar and pivoted at its upper 100 end, and a connecting train extending forwardly from said arm to said drive-link, said connecting train including a transmitting link, and also including a sub-lever pivoted upon the machine-frame and connected 105 at one end to said drive-link and having a movement-accelerating engagement with the main guide-link of the type-linkage, said engagement including a substantially radial slot in the main guide-link hub, and a pin on said sub-lever and engaging the outer end of said slot and moving towards the pivot of the 110 sub-lever during the printing stroke, said sub-levers radially mounted in the planes of the type-linkages, and each including a rearwardly-extending arm engaging the slot, and a downwardly-extending short arm pivoted 115 to said driving link, springs for returning said linkages to normal positions, ribbon-vibrating means and carriage-feeding means universally engageable by the rear arms of said key-levers.
12. In a typewriting machine, the combination with a platen upon which the printing line is visible, of a system of folded radial type-linkages movable rearwardly to strike 120 squarely upon the platen and capable of substantial manifolding, the type-linkages being arrested by the platen only, each linkage including a front guide-link and a rear drive or main link, each pivoted on the framework of the machine, and a cross-link pivoted upon 125 the free ends of said links; said cross-link resembling an elbow at the free end of which is fixed a lower and upper case type-block rigid with said cross-link, a type-rest, the types facing downwardly, keys in front of said type-linkage system, levers for said keys, each lever including a key-stem, a bar extending rearwardly beneath the type-linkages, and an arm extending up in rear of the type-linkages from said bar and pivoted at its upper 130 end,

the free ends of said links; said cross-link resembling an elbow at the free end of which is fixed a lower and upper case type-block rigid with said cross-link, each key-drive including 5 an arm extending up in rear of the system of type-linkages and operated by the key, and sub-levers having pin-and-slot movement accelerating engagement with the main drive-link and also having an operating arm operatively connected to said upright arm by a movement-transmitting device.

12. In a typewriting machine, the combination with a platen upon which the printing line is visible, of a system of folded radial type-linkages movable rearwardly to strike 15 squarely upon the platen and capable of substantial manifolding, the type-linkages being arrested by the platen only, each linkage including a front guide-link and a rear drive 20 or main link, each pivoted on the framework of the machine, and a cross-link pivoted upon the free ends of said links; said cross-link resembling an elbow at the free end of which is fixed a lower and upper case type-block 25 rigid with said cross-link, a type-rest, the types facing downwardly, keys in front of said type-linkage system, levers for said keys, each lever including a key-stem, a bar extending rearwardly beneath the type-linkages, 30 and an arm extending up in rear of the type-linkages from said bar and pivoted at its upper end, and a connecting train extending forwardly from said arm to said drive-link, said connecting train including a transmitting 35 link, and also including a sub-lever pivoted upon the machine-frame and connected at one end to said drive-link and having a movement-accelerating engagement with the main guide-link of the type-linkage, said key-levers substantially parallel, said drive-links 40 extending forwardly from said upwardly-extending, approximately parallel arms, and said sub-levers working in substantially the same planes as their respectively associated linkages, the width of the sub-lever system being approximately equal to the width of the key-lever system and the system of drive-links.

13. In a typewriting machine, the combination with a platen upon which the printing line is visible, of a system of folded radial type-linkages movable rearwardly to strike 50 squarely upon the platen and capable of substantial manifolding, the type-linkages being arrested by the platen only, each linkage including a front guide-link and a rear drive or main link, each pivoted on the framework of the machine, and a cross-link pivoted upon the free ends of said links; said cross-link resembling an elbow at the free end of which is 55 fixed a lower and upper case type-block rigid with said cross-link, a type-rest, the types facing downwardly, keys in front of said type-linkage system, levers for said keys, each lever including a key-stem, a bar extending 60

rearwardly beneath the type-linkages, and an arm extending up in rear of the type-linkages from said bar and pivoted at its upper end, and a connecting train extending forwardly from said arm to said drive-link, said 70 connecting train including a transmitting link, and also including a sub-lever pivoted upon the machine-frame and connected at one end to said drive-link and having a movement-accelerating engagement with the main 75 guide-link of the type-linkage, said key-levers substantially parallel, said drive-links extending forwardly from said upwardly-extending approximately parallel arms, and said sub-levers working in substantially the 80 same planes as their respective associated linkages, the width of the sub-lever system being approximately equal to the width of the key-lever system and the system of the drive-links, the line of articulation of the 85 drive-links to the lever-arms being above the middle sub-levers and below the sub-levers at the sides of the system, and the links inclining forwardly up and down according to the 90 positions of the sub-levers; the key-levers being pivoted on a horizontal transverse rod at their upper ends.

14. In a typewriting machine, the combination with a platen, of a system of two-case type folded noise-reducing linkages to print 95 on the visible side of the platen, each including a rear drive-link and a front follower link, both links pivoted upon the machine-frame, and a type-carrier pivoted upon the free ends of both links and having an elbow-extension carrying the type, the latter rigidly fixed upon the free end of said elbow and resting at the rear of the system of linkages, and key-driven means for starting each type-linkage gradually into unfolding motion, and accelerating them to highest speed during the main portion of the key-stroke until unfolded, and then slowly floating the unfolded types towards the platen, said linkages being 100 formed, proportioned and located to further decelerate the types sharply at their close approach to the platen, while the free ends of the drive and follower links continue at maximum speed, to utilize the momentum of the 105 hand of the operator, by causing the hand to be arrested by the engagement of the type with the platen, the shock of arresting the linkage and the hand being sufficient to impress the type clearly upon the paper on the platen.

15. The combination of a system of substantially parallel key-levers working in substantially vertical planes and having at their forward ends key-bearing stems, and extending rearwardly from the keyboard, and having at their rear ends upwardly-extending arms pivoted substantially in a horizontal transverse line at their upper ends at a level higher than the keyboard, pull-links pivoted 125 at their rear ends to the upstanding arms and 130

- extending forwardly, said pull-links pivoted in a substantially horizontal line, an arcuate system of bell-cranks above the rearwardly-extending portions of said key-levers and behind the keyboard and forward of the upwardly-extending arms, said levers radiating substantially from the printing point of the machine, the links at the sides of the system extending forwardly and upwardly to said 5 bell-cranks, and the middle links of the system extending forwardly and downwardly to said bell-cranks, said bell-cranks having outwardly-radiating short arms to which said links are connected at their forward ends, 10 and also having rearwardly-extending drive-arms, said forwardly-extending links being approximately parallel with the working planes of the key-levers and also approximately lying in the planes of their respective 15 bell-cranks or sub-levers, a system of rearwardly-striking, squarely-striking type-linkages radiating substantially from the printing point and including main drive guiding links pivoted at their outer ends upon the 20 framework of the machine in an arc substantially concentric with the printing point and below the same and above said bell-cranks, said drive-links having radially-slotted drive-arms radiating outwardly from their 25 pivots and engaged by drive-pins on the outer ends of the long arms of said bell-cranks in a manner to give extraordinary leverage of the keys upon the type-linkages at the beginning of the key-stroke and to decrease the 30 leverage of the keys upon the type-linkages to subnormal near or at the end of the printing stroke, each linkage also comprising a radiating guide-link pivoted at its outer end upon the machine-frame and forward of said 35 drive-link, and a type-bearing link having its type rigid therewith and including upper and lower case type-faces, said type-link pivoted upon the free ends of said drive-link and said guide-link, a triangle being formed by 40 the pivots and the type-end of the type-link, the linkages normally folded down below the printing point and in rear of the drive-links with the types below the free ends of the 45 drive and guide links, said types having pendent guide-tongues, and fixed guiding means below the printing point engageable by said tongues, the type-links at the sides of the system overlying said guide when standing at the printing point, the types at the 50 sides of the middle of the system forming various angles with the type-linkages, and being guided only laterally by the center guide, and means for guiding the free ends of the guide-links. 55
16. A system of type-actions including folded noise-reducing type-linkages, each linkage having a drive-link, a guide-link, and a type-link, a system of keys, and leverage-decreasing connections from the keys to the type-linkages; the distance between the free ends 60 of the drive and guide links being substantially less than the distance from the free end of the drive-link to the type, thereby giving the type-end of the linkage an accelerated unfolding movement during the main portion of the key-stroke, and thereafter translating the type-link bodily rearwardly in a direction radial to the platen-axis, the type normally facing downwardly at the rear of the guide-link fulcrum, the free end of the drive-link being near the fulcrum or fixed pivot of the guide-link; said guide-link, after unfolding, swinging at its free end rearwardly and downwardly relatively to the free end of the drive-link, to rock the floating type-link forwardly about the free end of the drive-link, and thereby decelerate the type relatively to the rearwardly-swinging free ends of the drive and guide links; the leverage-changing connections to the drive-link 65 having maximum leverage on the linkage at the beginning of the printing stroke, and minimum leverage on the linkage at the completion of the printing stroke. 70
17. A system of type-linkages each including a drive link, a follower link, a type-link mounted on said links, said type-link formed of plates or laminations enfolding the other links, one lamination being prolonged to form a neck and a head, and a two-case type 75 fastened upon said head, the neck-portion of each of substantially all of the type-bars being bent sidewise to bring the center of the lower-case type substantially into the working plane of the type-bar, said neck having another bend to give the proper angle to the type. 80
18. In a typewriting machine, for use with an ink-ribbon, the combination with a platen and a center-type-guide, of a system of normally-folded radial noise-reducing type-linkages movable rearwardly against the front of the platen, each linkage including an upstanding front guide-link and a forwardly-extending cumbent rear drive or main link, 85 each of said links pivoted to the framework of the machine, and a cross-link normally extending downwardly from the front link and pivoted at its lower portion to the forward end of the drive-link, said cross-link 90 having an elbow normally extending rearwardly and having upon its rear end a lower and upper case type-block rigid with said cross-link, a system of keys, and key-driven trains extending to said type-linkages and 95 including a system of sub-levers, means being provided in each train to co-operate with the sub-lever for rapidly decreasing the leverage of the key upon the type-linkage while rapidly unfolding the latter, the linkage being 100 completely unfolded at type-impressing position, with the two pivots of the drive-link substantially in line with the printing point on the platen, to float the type slowly in a path radial of the platen-axis, for pressing 105 110 115 120 125 130

the type squarely against the platen and for enabling the type to clear the center-type-guide.

19. A system of type-linkages as set forth in claim 18, in which each guide-link is mounted so that its free end dips downwardly and rearwardly sufficiently to retard the type end of the elbow relatively to the free end of the drive-link as the type is approaching the platen in said radial path, to effect substantial diminution of the speed of the type end of the elbow while said drive-link completes its printing stroke at maximum speed, together with the guide-link, for utilizing the arrest of the operator's hand and of the linkage, to deliver a low-speed, forced, quiet impression of the type upon the platen.

20. A system of type-linkages as set forth in claim 18, in which the sub-levers are pivoted upon the framework, and each forms one member of a leverage-reducing element.

21. In a typewriting machine, for use with an ink-ribbon, the combination with a platen, of a system of normally-folded radial noise-reducing type-linkages movable rearwardly to strike squarely upon the platen, each linkage including a front upstanding guide-link and a rear, cumbent, forwardly-extending drive-link, each of said links pivoted upon the framework of the machine, and a cross-link connecting the three ends of said link, said cross-link having a rearwardly-extending elbow carrying upper and lower case types, a system of keys, and a system of connecting trains to enable said keys to drive said linkages, said trains including a system of sub-levers working in radial planes corresponding with the radial planes of said drive-links, and means being provided in said connecting trains for rapidly decreasing the leverage of the keys upon the linkages throughout the principal portions of the type-driving strokes of the keys.

22. A type-operating mechanism as set forth in claim 21, having the radial sub-levers pivoted at their forward ends and extending rearwardly, said drive-links having radial slots and said sub-levers having pins working in said slots and swinging nearly towards the pivots of said drive-links, to effect rapid decrease in the leverage of each key upon the type-linkage throughout nearly all of the printing stroke.

23. In a typewriting machine, for use with an ink-ribbon, the combination with a platen, of a system of normally-folded radial noise-reducing type-linkages movable rearwardly to strike upon the platen, each linkage including a front upstanding guide-link and a rear, cumbent, forwardly-extending drive-link, each of said links pivoted upon the framework of the machine, and a cross-link connecting the three ends of said link, said cross-link having a rearwardly-extending elbow carrying upper and lower case types, a sys-

tem of keys and a system of connecting trains to enable said keys to drive said linkages, said connections including a system of key-levers extending forwardly under said linkages and having key-stems at their forward ends and also having arms extending up in rear of said linkages, and means operated by said rear arms and extending forwardly to operate said linkages.

24. A type-operating mechanism as set forth in claim 21, in which the connecting trains include a system of U-shaped key-levers extending forwardly under said linkages and have forward stems carrying the keys, and also have arms extending up in rear of the linkages, and links extending forwardly from said rear arms and connected at their forward ends to said sub-levers.

25. In a typewriting machine, for use with an ink-ribbon, the combination with a platen, of a system of folded radial noise-reducing type-linkages movable rearwardly to strike squarely upon the platen, each linkage including a guide-link and a drive-link, and a cross-link connecting the three ends of said link, said cross-link having an elbow carrying types, a system of U-shaped key-levers extending forwardly under said linkages and having stems carrying the keys, and also having arms extending up in rear of the linkages, and means operated by said rear arms to operate said type-linkages, and a carriage-feeding universal bar also operated by said rear arms of said key-levers.

26. In a typewriting machine, for use with an ink-ribbon, the combination with a platen, of a system of normally-folded radial noise-reducing type-linkages movable rearwardly against the front of the platen, each linkage including an upstanding front guide-link and a forwardly-extending cumbent rear drive or main link, each of said links pivoted to the framework of the machine, and a cross-link normally extending downwardly from the front link and pivoted at its lower portion to the forward end of the drive-link, said cross-link having an elbow normally extending rearwardly and having upon its rear end a lower and upper case type-block rigid with said cross-link, a system of keys, key-driven trains extending to said type-linkages, a center guide for said types, and a guide-comb engaging the linkages near the articulations of the guide-links to the type-links.

27. In a front-strike typewriting machine, the combination with a platen, of a system of folded pivotal type-actions including cumbent carriers having types on their rear ends below the platen and facing downwardly, each carrier having a plurality of types, forward and rear arms upon which each type-carrier is pivoted at its front, the forward arm upstanding and the rear arm cumbent, both arms pivoted to the framework, and fixed radial lat-

eral guides for the upper portions of the forward arms, in proximity to said carriers to guide the latter laterally.

28. In a front-strike typewriting machine, 5 the combination with a platen, of a system of pivotal type-actions including cumbent carriers having types on their rear ends below the platen and facing downwardly, each carrier having a plurality of types, forward and rear 10 arms upon which each type-carrier is pivoted at its front, the forward arm upstanding and the rear arm cumbent, both arms pivoted to the framework, and fixed lateral guides for the type-carriers at their articulations to the 15 front arms.

29. In a front-strike typewriting machine, the combination with a platen, of a system of pivotal type-actions including cumbent carriers having types on their rear ends below 20 the platen and facing downwardly, and forward and rear arms of substantially equal length upon which each type-carrier is pivoted at its front in non-parallel relation, said arms set to tip the type-carrier and thereby 25 decelerate the movement of the type at the terminal portion of its printing stroke against the platen without changing the speed of the type-carrier at its point of pivoting to the rear arm which carries it.

30. In a front-strike typewriting machine, 30 the combination with a platen, of a system of pivotal type-actions including cumbent carriers having types on their rear ends below the platen and facing downwardly, each carrier having a plurality of types, forward and 35 rear arms upon which each type-carrier is pivoted at its front, the forward arm upstanding and the rear arm cumbent, both arms pivoted to the framework, the carrier and the rear 40 arm in their printing strokes first turning to upright positions and the carrier then floating rearwardly upon said arms, operating means, and a lateral type-guide having opposite flaring jaws extending up to the printing line 45 and fitting to and guiding the types by their lower ends.

31. The combination of a segmental frame, 50 slotted segments thereon, sets of arms pivotally mounted in said segments, a set of type-carriers pivoted upon said sets of arms, and a platen against the front side of which said type-carriers strike, a guide being provided upon said segments at the upper ends of the arms in one set.

32. In a front-strike typewriting machine, 55 the combination with a platen, of a center type-guide, a system of folded pivotal type-linkages including cumbent carriers having types on their rear ends below the platen and facing downwardly, each type-carrier having a plurality of types thereon, and forward and rear arms on which each type-carrier is pivoted at its front, the forward arm upstanding and the rear arm cumbent, both 60 arms so pivoted to the framework and so

proportioned that the carrier in its printing stroke first completely unfolds, and then floats rearwardly upon said arms, the type for a substantial distance moving perpendicularly to the platen in said center guide after the complete unfolding of the type-bar. 70

33. In a front-strike typewriting machine, the combination with a platen, of a center type-guide, a system of folded pivotal type-linkages including cumbent carriers having 75 types on their rear ends below the platen and facing downwardly, each type-carrier having a plurality of types thereon, forward and rear arms on which each type-carrier is pivoted at its front, the forward arm upstanding and the rear arm cumbent, both arms so pivoted to the framework and so proportioned that the carrier in its printing stroke first completely unfolds, and then floats rearwardly upon said arms, the type for a substantial 80 distance moving perpendicularly to the platen in said center guide after the complete unfolding of the type-bar, and fixed radial lateral guides for said linkages between the platen and the lower pivotal points of said forward and rear arms, said guiding means in proximity to said type-carrier, to insure the type being directed into said central type-guide. 85

34. In a front-strike typewriting machine, 95 the combination with a platen, of a system of pivotal type-linkages normally folded, each linkage including a cumbent carrier having a plurality of types on its rear end below the platen and facing downwardly, and forward and rear arms articulated to the framework and upon which each type-carrier is pivoted at its front in folded relation, said type-carrier movable on said arms to completely unfolded position, the types upon all 100 of the linkages, after unfolding, moving in a common path perpendicularly to the platen, said arms in each linkage being connected to the type-carrier in a manner to tip the type-carrier as it approaches the platen to carry 105 its front pivot downwardly relatively to its rear pivot, to retard the type as it moves through said common path to the platen. 110

35. In a front-strike typewriting machine, 115 the combination with a platen, of a system of folded pivotal type-linkages including cumbent carriers having types on their rear ends below the platen and facing downwardly, each carrier having a plurality of types, forward and rear arms upon which each type-carrier is pivoted at its front, the forward arm upstanding and the rear arm cumbent, both arms pivoted to the framework, the carrier and the rear arm in their printing 120 strokes first fully unfolding to upright positions and the carrier then floating rearwardly upon said arms through a common path perpendicularly to the platen, and operating means; said front arm mounted and proportioned to tip the unfolded carrier forwardly 125 130

relatively to the other arm, thereby retarding the type while traveling through said common path at the final portion of its printing stroke, while the remainder of the linkage 5 keeps on at full speed and by its momentum exerts momentary pressure upon the arrested type.

36. In a front-strike typewriting machine, the combination with a platen and an inking ribbon, of a system of type-heads having types to strike upon the front of the platen, said types normally facing downwardly, each type-head having a plurality of types thereon, a system of normally folded swinging elbows forming carriers upon whose free ends said type-heads are fixed, and swinging arms supporting and operating said elbows to unfold the same rapidly and then move the types slowly against the platen in a path vertical to the platen, said path being common to all the type-carriers, said arms formed and mounted to tip said elbows forwardly about their pivots in the opposite direction from the printing movements of the types, while moving in said common path vertically to the platen, to effect a deceleration of the types relatively to said arms, to cause the types to make quiet impacts upon the platen of sufficient force to make clear impressions through the ribbon upon the work-sheet, each elbow having a relatively long arm carrying the types and a relatively short angular arm pivoted to said swinging arms.

37. In a typewriting machine, the combination with a platen, of a system of front-strike type-linkages, each carrying a plurality of types normally facing downwardly, each type-linkage including a pair of pivotally supported arms pivoted at their outer ends 40 to the framework and connected at their inner or upper ends by means of a type-carrier of elbow form normally folded, the type-carrier being pivotally mounted and first completely unfolded to carry the type rapidly to the vicinity of the printing point, and then floated rearwardly on said arms in a common path relatively to the platen while the linkage as a whole is traveling at maximum speed and the type is traveling at minimum speed.

38. In a typewriting machine, the combination with a platen, of a system of front-strike type-linkages, each carrying a plurality of types normally facing downwardly, each type-linkage including a pair of pivotally supported arms pivoted at their outer ends to the framework and connected at their inner or upper ends by means of a type-carrier of elbow form normally folded, the type-carrier being pivotally mounted and first completely unfolded to carry the type rapidly to the vicinity of the printing point, and then floated rearwardly on said arms in a common path relatively to the platen, and a set of radial guides for laterally guiding the linkages about midway between the printing

point and points of articulation of said arms to the framework.

39. In a front-strike typewriting machine using a ribbon, the combination with a series of radially-arrayed type-bars of the character described, of ribbon-vibrating mechanism including an actuating member located behind and substantially central of the radial array of type-bars, a ribbon-carrier, and means connecting said ribbon-carrier to said actuating means, said connecting means including a rock-shaft with arms at each end outside the zone of type-bar movement, said ribbon-carrier having yoke-like extensions connected to said arms and designed to clear 80 said zone.

40. In a front-strike typewriting machine, having a shiftable platen and using a ribbon, the combination with a series of radially-arrayed type-bars of the character described 85 and means movable to shift said platen, of ribbon-vibrating mechanism including an actuating member located behind and substantially central of the radial array of type-bars, a ribbon-carrier having a central ribbon-carrying portion overlying a zone through which the type-bars must move to print, and means connecting said ribbon-carrier to said actuating means, said connecting means including a rock-shaft movable with the movable 95 platen-shifting means, said rock-shaft having arms at each end outside the zone of type-bar movement, said ribbon-carrier having yoke-like extensions from its ribbon-carrying portion, said extensions connected to said 100 arms and designed to clear said zone.

41. In a front-strike typewriting machine having a platen, the combination with a series of radially-arrayed type-bars having type-heads rising from a retracted position 105 to printing position along an upward, forward and rearward path substantially as indicated, of a ribbon-carrier having a portion adjacent the printing point around which the ribbon is threaded, said ribbon-carrier having lateral extensions to clear the zone in which the type-bars move, and means, connected to said extensions, for vibrating said ribbon-carrier to present the ribbon at the printing point at each type-bar operation 115 to print.

42. In a front-strike typewriting machine, the combination with a platen and a series of radially-arrayed folded type-bars of the character described, said type-bars rising bodily 120 from a normally-cumbent folded position to an unfolded position to print at a single printing point, of a vibratory ribbon-carrier, and ribbon-vibrating means co-operating with said ribbon-carrier, said ribbon-carrier being 125 extended laterally for connection to said ribbon-vibrating means, so as to clear the zone in which said type-bars move as aforesaid.

43. In a front-strike typewriting machine, the combination with a platen, a system of 130

types, and a type-guide and a vibratory ribbon-guide both located in front of the platen at the printing point, of a system of type-linkages, each linkage including a rear drive-link and a front guide-link and also an elbow link pivoted upon said links and having a rear free end, each of said free ends having upper and lower case types fixed thereon, said linkages normally folded with the types at 5 the rear and facing downwardly and located underneath said type-guide and said ribbon-guide, and key-controlled means for operating said linkages; the links in each linkage being so formed, proportioned and located as 10 to rapidly lift or unfold the type end of the elbow link upwardly and forwardly in front of and above said center guide, and to float the unfolded elbow link rearwardly to carry 15 its type at relatively low speed and in a direction radial to the platen-axis to contact with the platen.

44. Typing mechanism as set forth in claim 43, in which said ribbon-guide forms part of a ribbon-vibrating mechanism including operating means extending laterally from said ribbon-guide sufficiently to clear the type-linkage system.

45. Typing mechanism as set forth in claim 43, and having laterally-extending operating 30 means in the form of a yoke branching in opposite directions from said ribbon-guide, a transverse rock-shaft operated by the keys, and arms upon said rock-shaft engaging said yoke to vibrate said yoke and ribbon-guide.

35 46. In a front-strike typewriting machine,

the combination with a platen, a system of types, and a type-guide located in front of the platen at the printing point, of a system of type-linkages, each linkage including a rear drive-link and a front guide-link and also an elbow link pivoted upon said links and having a rear free end, each of said free ends having upper and lower case types fixed thereon, said linkages normally folded with the types at the rear and facing downwardly and located underneath said type-guide, and key-controlled means for operating said linkages; the links in each linkage being so formed, proportioned and located as to rapidly lift or unfold the type end of the elbow link upwardly and forwardly in front of and above said center guide, and to float the unfolded elbow link rearwardly to carry its type at 40 relatively low speed and in a direction radial to the platen-axis to contact with the platen, 45 said linkages working in converging planes radiating from the printing point, and said type-links having outward type-carrying bends at their tips, said bends at various angles, and the apices of said angles being substantially coincident with the printing point, 50 and said tips having guiding nibs extending downwardly from the types to enter said type-guide, the latter being immediately below the printing point.

47. Typing mechanism as set forth in claim 46, having means for laterally guiding said linkages in proximity to the articulations of the type-links to the guide-links.

BURNHAM C. STICKNEY.
